UNITED STATES PATENT OFFICE.

LEONARD C. HOOVER, OF CLEARRUN, KENTUCKY.

WIRE FENCE.

SPECIFICATION forming part of Letters Patent No. 706,562, dated August 12, 1902.

Application filed January 25, 1902. Serial No. 91,245. (No model.)

To all whom it may concern:

Be it known that I, LEONARD C. HOOVER, a citizen of the United States, residing at Clearrun, in the county of Ohio and State of Kentucky, have invented a new and useful 5 Wire Fence, of which the following is a specification.

This invention relates to certain new and useful improvements in wire fences; and the 10 object of the same is to provide a series of interlocking pickets or stays in conjunction with a plurality of runners and having laterally-projecting members which unite the several stays between the planes of the runners, 15 and thereby produce a compact, strong, and durable fence, as well as ornamental configurations, whereby when the stays are mounted an artistic effect is produced.

The invention consists in the construction 20 and arrangement of the several parts, which will be more fully hereinafter described and claimed.

In the drawings, Figure 1 is an elevation of 25 a fence embodying the features of the invention. Fig. 2 is a similar view showing a slight change or modification in the formation of the improved fence.

Similar numerals of reference are employed 30 to indicate corresponding parts in the several views.

The numeral 1 designates wire runners which are arranged in planes parallel, as usual, and supported by posts 2. The posts will be arranged at such distances apart as 35 to provide well-defined panels, and between the posts in each panel the improved stays or pickets 3 are vertically positioned and connected to the said runners and to each other, as will be presently explained. Referring to 40 Fig. 1, each stay is composed of a series of inverted triangular attaching-loops 4, having outer eyes 5 to engage the runners, and central upstanding twisted necks 6, having the wire strands thereof extended laterally in 45 planes parallel with and between the said runners to form elongated connecting-loops 7, which are continued into the lower reduced extremity of each of the loops 4 above in regular succession by binding-twists 8. The lower 50 reduced extremities of the lowermost series of loops 4 are attached by staples or analog-

gous devices 9 to stakes or other anchors in the ground beneath, and the uppermost series of the said loops have the necks 6, terminating in ornamental head-loops 10, which 55 produce an artistic appearance at the top of the fence. The ends of the loops 7 of the intermediate stay are interlocked with the ends of the adjacent loops of the outer stays of each panel, and the ends of the loops of the said 60 outer stays contiguous to the posts are secured to the latter by staples or other similar devices 12. From the foregoing, it will be seen that a strong panel construction results, and the completed fence presents a pleasing 65 appearance. Moreover, the several parts can be quickly assembled, and the interconnection of the loops 7 provides intermediate braces which contribute materially in producing a solid fence fabric wherein there is a 70 unity of reinforcement.

The form of the fence shown by Fig. 2 is substantially like that described, and the same reference-numerals have been applied to corresponding parts. The difference resides in the formation of intermediate longitudinally-extending loops 13, which emanate 75 from a point between the attaching-loops 4 and are located exclusively on one side of the stays or pickets. In this instance also the 80 necks heretofore set forth are varied by the construction of short binding-bends 14, from which the said loops 13 begin, and each loop 13 interlocks with the starting portion of the similar loop from the stay. In this form of 85 the fence also the stays between the upper runners are devoid of the said loops 13, and the end loops 13 or those of one stay are secured to the adjacent post. This form of the fence is not as strong as the one first described, but demonstrates the possibility of 90 varying the arrangement without departing from the principle of the invention, and it will be understood that other changes may be made in the minor details of bending and 95 directing the intermediate loops.

Having thus described the invention, what is claimed as new is—

1. In a fence, the combination of a plurality of runners, and stays having longitudinally oppositely extended parts provided with eyes to receive the runners and intermediate 100

longitudinally-extending interlocked loops between the planes of the runners, substantially as described.

2. In a fence, the combination with runners, of stays having inverted triangular loops with opposite eyes to receive the runners and intermediate longitudinally-extending interlocked loops between the planes of the runners.
- 10 3. In a fence, the combination of a plurality of runners, and vertically-disposed stays

or pickets having interlocking loops extending longitudinally from opposite sides thereof and located between the planes of the runners.

In testimony that I claim the foregoing as my own I have hereto affixed my signature in the presence of two witnesses.

LEONARD C. HOOVER.
